UNITED STATES PATENT OFFICE.

FRANK STEBBING, OF WASHINGTON, DISTRICT OF COLUMBIA.

LIFE-PRESERVER.

1,273,687.

Specification of Letters Patent. Patented July 23, 1918.

Application filed March 29, 1918. Serial No. 225,529.

To all whom it may concern:

Be it known that I, FRANK STEBBING, a citizen of the United States, residing at Washington, in the District of Columbia, 5 have invented new and useful Improvements in Life-Preservers, of which the following is a specification.

This invention relates to life preservers and it consists in the novel features herein- 10 after described and claimed.

An object of the invention is to provide a life preserver of simple and durable structure adapted to be applied to the human body and which may be inflated by the 15 wearer in order to add buoyancy to the same to sustain the body in floating position in water.

With this object in view the life preserver comprises two pouches or sacks 20 adapted to be applied one in front of the body and the other at the back thereof, the said pouches being connected together by means of a belt which passes around the waist of the wearer. The pouches are fur- 25 ther connected together by means of straps which pass over the shoulders and communicating tubes which also pass over the shoulders. A valve controlled means is pro- 30 vided at the forward pouch through which the wearer may blow air into the same and straps are connected with the belt and adapt- 35 ed to pass under the body of the wearer whereby the belt is restrained against moving up along the waist.

35 In the accompanying drawings:—

Figure 1 is a perspective view of a human body with the life preserver applied;

Fig. 2 is a side elevation of the same showing the life preserver in section;

40 Fig. 3 is a plan view of the life preserver detached;

Fig. 4 is a detailed sectional view of the life preserver;

Fig. 5 is a plan view, with parts in sec- 45 tion of inner sacks and tubes used in the life preserver;

Fig. 6 is a side elevation of the modified form of the life preserver showing parts broken away;

50 Fig. 7 is a detailed sectional view of a mouthpiece adapted to be used for inflating the life preserver;

Fig. 8 is a perspective view of a receptacle which may be used for inclosing and carry- 55 ing the life preserver.

As illustrated in Figs. 1, 2 and 3 of the

drawing, the life preserver comprises a forward pouch or sack 1 and a rear pouch or sack 2. These sacks or pouches are connected together by means of a belt 3 which 60 is adapted to pass around the waist of the wearer when the life preserver is applied. Straps 4 are connected at one end with the belt 3 and detachably connected at their other ends with the said belt and are adapt- 65 ed to pass under the body of the wearer whereby the said belt is prevented against moving up along the waist of the wearer. The detachable connection between the said straps and the belt are in the form of snap 70 hooks and eyes 5 of conventional pattern. These connections are located at the forward portions of the belt and straps. Straps 6 connect the upper portions of the sacks or pouches 1 and 2 together and are adapted 75 to lie over the shoulders of the wearer as best shown in Fig. 2 of the drawing.

Tubes 7 connect at their ends with inner pouches 8 located within the sacks 1 and 2 and the said tubes are located at the oppo- 80 site sides of the throat of the wearer when the preserver is applied and extend over the shoulders. The said tubes 7 are covered by casings 9 and the said casings may be opened at their upper portions in order to gain 85 access to the said tubes for repairing or other purposes. The edges of the casings 9 may be secured together by means of se- 90 curing devices 10 in the form of glove fas- teners of conventional form. The casings 9 may be opened by disconnecting the se- 95 curing devices. The tubes 7 and pouches 8 are preferably made from thin rubber. A tube 11 is connected with the forward sack 1 and the pouch 8 located therein and a nipple 12 95 is connected with the upper end of the tube 11. The upper portion of the tube 11 is held in position at the top of the sack 1 by means of a strap 13 as best shown in Fig. 1 of the drawing.

The nipple 12 is provided with a flap valve 14 best shown in Fig. 7 of the drawing. Also a mouth piece 15 is screwthreaded upon the nipple 12. A valve 16 is pro- 105 vided at or about the point of connection between the tube 11 and the sack 1 and may be used for closing the passageway through the tube 11.

In the form of the invention as shown in Fig. 6 of the drawing, the sacks 1 and 2 are 110 devoid of inner pouches and are preferably made of rubberized cloth or similar ma-

terial whereby they are rendered water-proof and airtight. In other respects the general structural arrangement of the form as shown in Fig. 6 is the same as that hereinbefore described.

A receptacle 17 is shown in Fig. 8 of the drawing, in the form of a satchel, and may be provided for holding the life preserver when the same is being carried or transported.

When the life preserver is applied the parts assume the position on the body of the wearer substantially as shown in Figs. 1 and 2 of the drawing, wherein it will be seen that the upper portion of the sack 1 is directly under the chin of the wearer and the wearer may blow through the mouth-piece 15 and the tube 11 and thereby inflate the pouches in the sacks 1 and 2 or the sack 20 as illustrated in Fig. 6. Thus when the wearer is in water buoyancy is added to the upper portion of the body whereby the head is supported above the surface of the water and the device performs its function as a life preserver.

From the foregoing description taken in conjunction with the accompanying drawing, it will be seen that a life preserver of simple and durable structure is provided

and that the same may be easily and quickly applied to the body of the wearer, inflated and removed therefrom.

Having described the invention what is claimed is:

1. A life preserver comprising sacks adapted to be applied to the forward and rear portions of the body of a wearer, shoulder straps connecting the sacks together, tubes connecting the sacks together at points below their upper ends whereby the upper portions of the sacks may bear against the base of the head of the wearer and means for inflating the sacks and tubes.

2. A life preserver comprising sacks adapted to be applied to the forward and rear portions of the body of a wearer, shoulder straps connecting the sacks together, tubes connected with the sacks at points below their upper ends whereby the upper ends of the sacks may bear against the base of the head of the wearer, casings surrounding the tubes, means for detachably connecting the sides of the casings together, and means for inflating the sacks and tubes.

In testimony whereof I, affix my signature.

FRANK STEBBING.
